(74) **Attorney, Agent, or Firm:** Xiaofang Zhong

(57) **CLAIM**

The ornamental design for camera clamp, as shown and described.

DESCRIPTION

FIG. 1 is a front, left and top perspective view of a camera clamp showing my new design;

FIG. 2 is a rear, right and bottom perspective view thereof;

FIG. 3 is a front, left and top perspective view thereof, shown in an alternate configuration;

FIG. 4 is a front elevational view thereof;

FIG. 5 is a rear elevational view thereof;

FIG. 6 is a left view thereof;

FIG. 7 is a right view thereof;

FIG. 8 is a top plan view thereof;

FIG. 9 is a bottom plan view thereof;

FIG. 10 is an enlarged view of a portion labeled as 10 on FIG. 1; and,

FIG. 11 is an enlarged view of a portion labeled as 11 on FIG. 1.

The long dash-dash-long dash line shown in FIGS. 1, 10, and 11 depict enlargement boundaries that form no part of the claimed design.

1 Claim, 11 Drawing Sheets
